UNITED STATES PATENT OFFICE.

JAMES A. BRANTLEY, OF SAND SPRINGS, OKLAHOMA.

MINING-MACHINE.

1,299,905.

Specification of Letters Patent. Patented Apr. 8, 1919.

Application filed February 3, 1917. Serial No. 146,414.

To all whom it may concern:

Be it known that I, JAMES A. BRANTLEY, citizen of the United States, residing at Sand Springs, in the county of Tulsa and State of Oklahoma, have invented certain new and useful Improvements in Mining-Machines, of which the following is a specification.

My present invention pertains to mining machines; and it has for its general object to provide a mining and tunneling machine, designed more especially for coal mining or cutting operations, and constructed to travel on the ground or on rails, at the election of the operator, to turn as on a pivot, to afford a plurality of speeds, and to place its cutting mechanism at various angles, as occasion demands.

Other objects and advantageous features of the invention will be fully understood from the following description and claims when the same are read in connection with the drawings, accompanying and forming part of this specification, in which:

Figure 1 is a side elevation of the machine constituting the best practical embodiment of my invention that I have as yet devised.

Fig. 2 is an enlarged rear elevation of the same.

Fig. 3 is a detail plan with the top of the casing body removed.

Figs. 4 and 5 are detail longitudinal vertical sections taken in the planes indicated by the lines 4—4 and 5—5, respectively, of Fig. 3.

Fig. 6 is an enlarged cross-section on line 6—6 of Fig. 3.

Figs. 7 and 8 are details hereinafter specifically referred to.

Fig. 9 is a fragmentary cross-section through the forward portion of the casing body.

Figs. 10, 11 and 12 are detail sections; Figs. 10 and 11 being taken on the lines 10—10 and 11—11, respectively, of Fig. 8.

Fig. 13 is a cross-section through the forward part of the casing body.

Fig. 14 is a cross-section on line 14—14 of Fig. 3.

Figs. 15 and 16 are detail broken views of portions of the mechanism.

Similar numerals of reference designate corresponding parts in all of the views of the drawings.

Among other elements my novel machine comprises a casing-like body 1 which in

common with the remainder of the machine is preferably constructed of steel or of metal compatible with its purpose.

Suitably supported and secured in the body 1 is an electric motor 2 which is the type of motor I prefer to employ. I would have it understood, however, that in lieu of an electric motor, an internal combustion engine or any other kind of motor may be employed without involving departure from the scope of my invention as defined in my appended claims.

In the present embodiment of the invention the motor 2 is supplied with current through the trailing wires 3, Figs. 4 and 5, and the other appurtenances common to electric motors, which appurtenances are carried by the body 1 but need not be described in detail.

The armature shaft 4 of the motor extends forwardly from the remainder thereof, in the longitudinal center of the machine, and interposed between said shaft 4 and a shaft 5 which extends through the forward wall of body 1 and carries a pinion 6, is a clutch 7. This clutch 7 may be of any suitable construction, and is designed to be operated by a lever 8 located at the back of the body 1 through a connection which *per se* forms no part of my invention and is therefore not illustrated. When the members of the clutch are disengaged the machine may be moved, turned and handled by its own power without operation of the cutting mechanism which derives motion from the shaft 5 as hereinafter set forth. When, however, the members of the clutch are engaged, the shaft 5 and the cutting mechanism alluded to will be actuated. From this it follows that while not essential to the practice of my invention, the clutch 7 is preferable because the cutting mechanism may be left idle and danger and waste of current may be avoided incidental to the manipulation of the remainder of the machine.

On the armature shaft 4 of the motor is a worm 9, and intermeshed with and driven by said worm 9 is a worm-wheel 10, fixed on a transverse shaft 11, extending between and journaled in the side walls of the body 1. Mounted to slide on and turn with said shaft 11, at opposite sides of the worm-wheel 10, are combined friction and spur gears 12. These gears 12 respectively comprise a soft-steel hub 13, Fig. 12, feathered on the shaft

11, a central steel disk 14 loosely though snugly mounted on the hub 13 and having peripheral teeth 15, friction sections 16, of paper or fiber, loosely mounted on the hub 13 at opposite sides of the disk 14 and arranged with their smooth perimeters flush with the bottoms of the interdental spaces in the disk 14, and a nut 17 threaded on the hub 13 and adapted to tighten the disk 14 5 and the sections 16 against a flange on the hub. In the outer portions of the hubs 13 of the compound gears 12 are circumferential grooves in which are sectional rings 17^a having studs 17^b disposed in upright bifurcated levers 18 through the medium of which the compound gears 12 are moved horizontally on shaft. Each of the gears 12 is arranged back of and opposed to an inclined steel disk 20, and each disk 20 is provided 10 in its face with three (more or less) circular series of indentures 21; the indentures of each series being spaced to receive the teeth 15 of the gears 12. The disks 20 are feathered on forwardly and downwardly inclined 15 shafts 22, which are journaled in bearings 23, 24, in body 1 and are equipped with worms 25. The said worms 25 are intermeshed with worm wheels 26, fixed on shafts 27 on which are also fixed the exterior drive 20 and traveling wheels 28 of the machine.

In front of the disks 20 is a transverse shaft 30 on which is fixed an arm 31 to which is connected a rearwardly extending rod 32. This rod 32 is carried through the rear wall 35 of the body 1, and is connected exteriorly of the body to a lever 33 at the rear end of body 1 which lever is designed to be actuated to move the disks 20 toward and from the compound gears 12. Any suitable means 40 (not shown) may be employed to adjustably fix the lever 33 if such provision is deemed expedient.

Also fixed on the shaft 30 are arms 35. Connected with these arms 35, preferably in an adjustable manner, are yoke levers 36, and mounted at 37 in said yoke levers are studs on sectional rings 38 which are disposed in circumferential grooves 39 in steel members 40 loose on the shafts 22 and arranged back of the hubs on the disks 20. Between each of the said members 40 and each of the disk hubs are interposed a steel race annulus 41 and a steel ring 42 in which are anti-friction balls 43, interposed between 55 the member 40 and the ring 42 and adapted to lessen the friction when the disk 20 is thrust against its complementary gear 12. For the purpose of enabling each lever 36 to pull its respective disk 20 away from the operating gear 12, links 44 are pivoted to the sides of each lever 36. The rear portions of said links 44 receive pins 45 on a sectional ring 46 disposed in the circumferential groove 47 of the disk hub.

60 65 It being remembered that the traveling

wheels 28 are fixed on the shafts 27 and that said shafts 27 are driven by their respective shafts 22 through the permanently intermeshed gears 25 and 26, it will be understood that the traveling wheels 28 will be 70 rotated when the disks 20 are thrust and held against the gears 12 and will be permitted to remain at rest when the disks 20 are drawn and held away from the gears 12.

As before stated the gears 12 are adapted 75 to be moved by levers 18 lengthwise of the shaft 11, and by so moving said gears 12 and changing their positions relative to the centers of the disks 20, the speed of the traveling drive wheels 28 can be varied.

Again, when the gears 12 are moved across the centers of the disks 20 the direction of movement of the wheels 28 is reversed, but the same variations of speed are available as in the first instance. Moreover, it is to be 80 noted that the said construction constitutes positive driving connections for the independent operation of the driving wheels 28, so that one wheel 28 may be turned forwardly and the other backwardly to facilitate turning of the machine as on a pivot; also, that the three series of indentures in 85 each disk 20 afford positive driving connections at three different speeds forwardly or backwardly. I prefer to provide each disk 90 with three series of indentures 21, but it is obvious that the number of the series may be increased or diminished in the discretion of the manufacturer of the machine without affecting my invention.

100 Mounted on spindles carried by the body 1 and disposed in rear of the wheels 28 are traveling wheels 50, and mounted on the said wheels 28 and 50 are caterpillar tractor belts 51. It will also be noticed that the wheels 105 28 and 50 are flanged, as indicated by 52 to enable them to hold to rails as 53 when it is desired to move the machine on a railway instead of on the ground.

For the purpose of moving the compound 110 gears 12 relative to the centers of the disks 20 I provide the longitudinal rock shafts 54 which extend through the rear wall of the body 1 and are provided immediately back of said wall with cranks 55 through the medium of which they may be turned about their axes; said cranks 55 being provided as shown with means for adjustably fixing the shafts 54 to body 1. At their forward ends said rock shafts are provided with arms 56. 115 These arms are connected by pins 57 with the levers 18; the said pins being disposed and movable in slots 58 of the levers as illustrated.

120 Intermeshed with the pinion 6, which is beveled as shown, is a beveled gear 60, fixed on a shaft 61 that is journaled in a vertically revoluble frame 62, disposed immediately in front of the body 1. Also fixed on the shaft 61 is a sprocket gear 63. A bar 64 is fixed to 125

and extended forwardly from a frame 62^a that is loosely mounted to swing on the shaft 61 at right angles thereto, and carried on said bar at the forward end thereof is a 5 sprocket gear 65. Mounted on the gears 63 and 65 and actuated by the former is a sprocket belt 66 on which are carried cutter members 67 and pick members 68. I desire it distinctly understood, however, that I do 10 not confine myself to the employment of cutter members 67 and pick members 68 on the belt 66, but that, on the other hand, the said belt 66 may be provided with any other means for cutting or disintegrating coal or other 15 substance without involving departure from the scope of my invention as claimed.

Fixed on the frame 62^a and loosely receiving the shaft 61 is a gear 69 that describes the major part of a circle, and 70 is a toothed 20 dog through the medium of which the frame 62^a and the cutter bar 64 are held or locked at the angle desired. The said dog 70 is opposed to the toothed edge of gear 69, inside 25 one arm of the revoluble frame 62, and is connected to and movable into and out of 30 engagement with the gear 69 by hand levers 71, pivoted at 72 to said arm of frame 62.

The vertically revoluble frame 62 is loosely 35 mounted on the shaft 5, between the pinion 6 and the forward end of the body 1, and has fixed to its rear end a spur gear 73 that is opposed to said end of the body 1 and is held thereagainst by strap keepers 74 which however do not interfere with the turning of the gear.

Arranged at the forward end of the body 1 with its toothed perimeter in opposed relation to and intermeshed with that of the gear 73 is a pinion 75. Said pinion 75 is carried on a short, longitudinally-disposed shaft 76 journaled in the forward wall of the body 1. At its rear end and within the body 1 the shaft 76 is equipped with a beveled gear 77. This latter is arranged between beveled gears 78, carried by a common body 79 that is splined or feathered on a transverse shaft 80, and is provided at one end with a circumferentially grooved portion 81. This latter is for the reception of a sectional ring 82, 40 having pins 83 which are pivoted in the bifurcated portion 84 of a transversely arranged link 85. At its end remote from the gear body 79 the said link 85 is pivotally connected to an arm 86 on a longitudinally- 45 disposed rock shaft 87, journaled in the body 1 and extending through the rear wall thereof. Immediately in rear of the body 1 said shaft 87 is equipped with a handle 88 through the medium of which the shaft may be conveniently rocked to position either of the 50 gears 78 in mesh with the gear 77 or both out of engagement with said gear 77.

It will be understood that when the shaft 80 is rotated during the operation of the 55 machine, and when one of the gears 78 is

intermeshed with the pinion 77, the gear 73, frame 62 and the cutting mechanism will be turned in one direction about the shaft 5, and when the other gear 78 is engaged with the pinion 77 the turning movement of the parts 70 named will be in the opposite direction.

The shaft 80 is equipped with a sprocket gear 89, fast thereon, and is driven from the transverse shaft 9 through the medium of a sprocket gear 90 thereon, and a sprocket 75 belt 91 which connects the gears 89 and 90.

Loose on the shaft 80 is a miter gear 92 having a clutch member 93, and splined or feathered on said shaft 80 is a complementary clutch member 94 that is movable 80 through a lever 95 into and out of engagement with the member 93 to render the same fast and loose, respectively, on the shaft. The lever 95 is adapted to be actuated from the rear end of the body 1 through the 85 medium of an endwise movable rod 96, and a handle 97, disposed at the rear end of said body 1.

A miter gear 98 on a vertical shaft 99 is intermeshed with the gear 92, and hence 90 when gear 92 is clutched to shaft 80 the shaft 99 and the cleaning mechanism connected therewith will be driven. The cleaning mechanism referred to is for co-operation with longitudinal steel ducts 100, one 95 at each side of the bottom of the body 1, and said mechanism comprises a spur gear 99^a on shaft 99, short shafts 101 and 102 at the forward ends of the inner side walls of the ducts 100, a spur gear 101^a fixed on shaft 100 101 and intermeshed with the spur gear 99^a, sprocket gears 103 on the shafts 101 and 102 and connected by a sprocket belt 104, and constituting a cleaning belt which passes around the sprocket gears 103, through the 105 ducts 100 and around idler sprocket gears 106 in the lower rear corners of the body 1, and carries scrapers 107 which are spaced about eight inches apart. The rear transverse stretch of the said cleaning belt is 110 opposed as shown to an opening 108 in the lower rear portion of the body 1.

Manifestly by operating the handle 97 the machine attendant is enabled to start or stop the cleaning belt; the said belt being 115 rendered idle when the machine is not cutting, this with a view to avoiding unnecessary wear and saving power.

As is clearly shown in the drawings the rock shaft 87 is tubular throughout its 120 length and is open at its opposite ends. This provision is made for the endwise movement in said shaft of a rod 110 which is normally held in and returned to the position shown by a retractile spring 111. At its forward 125 end said rod 110 is pivoted to one end of a lever 112, fulcrumed at 113 against the forward wall of the body 1 and pivoted at its opposite end to a latch 114 which is guided in the said body wall and is adapted to enter 130

interdental spaces of or other apertures in the gear 73 with a view to locking the said gear and the frame 62 with the cutting mechanism in the position desired.

5 Against the rear end of the rod 110, one end of the handle 88 bears; the said handle being fulcrumed at 88^a to a bracket 88^b on an arm 88^c fixed to the tubular rock shaft 87, and being provided with a latch pin 88^d, 10 guided in the arm 88^c and adapted to enter apertures 88^e in the rear wall of the body 1. It will be manifest in this connection that when the handle 88 is swung rearwardly the latch pin is withdrawn from engagement 15 with the body wall and at the same time the rod 110 is moved forwardly, against the action of spring 111, to disengage latch 114 from the gear 73, after which the handle 88 and the arm 88^c may be swung to rock the 20 shaft 87 about its axis and position the gear body 79 as desired relative to the bevel gear 77 on the shaft 76.

In addition to the appurtenances hereinbefore enumerated, the body 1 is provided at 25 its rear end with an electric switch 120 and an electric circuit breaker 121. These and their connections are not of my invention, and being well known, it is not necessary to describe the same.

30 It will be appreciated from the foregoing that I have provided a cutting and tunneling machine that is possessed of large capacity, this being due to the facility with which the machine may be advanced and retracted as well as turned as a unit, and also to the facility with which the cutting mechanism may be manipulated and placed in various positions so as to operate to the best advantage. It will also be appreciated that 35 the efficiency of the machine is also due in large measure to the fact that all of its working parts are controlled from a single point, and that back of the body 1 where an attendant can position himself and watch and control the machine without subjecting himself to the danger of being injured by the cutting mechanism.

Having described my invention, what I claim and desire to secure by Letters Patent, 50 is:

1. In a mining machine, the combination of a body, a revolute frame at the front of the body, cutting mechanism carried by said frame, means for actuating said cutting mechanism, means for revolving said frame, means extending to the rear of the body for controlling said revolving means, and means for locking the frame against revolving; the latter means working 55 through the means for controlling the revolving means.

2. In a mining machine, the combination of a body, a revolute frame at the front of the body, cutting mechanism carried by 60 said frame, means for actuating said cutting

mechanism, means for revolving said frame, means for controlling said revolving means and including a tubular rock shaft, means for locking the frame against revolving, the latter means including a rod movable 70 through the tubular rock shaft, and a common handle for rocking the shaft and moving endwise the shaft.

3. In a mining machine, the combination of a body, a revolute frame at the front of 75 the body, cutting mechanism carried by said frame, means for actuating said cutting mechanism, means for revolving said frame, means for controlling said revolving means and including a tubular rock shaft, means 80 for locking the frame against revolving, the latter means including a rod movable through the tubular rock shaft, an arm on the rock shaft, and a handle fulcrumed on said arm and engaging the rod to move the 85 same endwise.

4. In a mining machine, the combination of a body, a revolute frame at the front of the body, cutting mechanism carried by 90 said frame, means for actuating said cutting mechanism, means for revolving said frame, means for controlling said revolving means and including a tubular rock shaft, means for locking the frame against revolving, the latter means including a rod movable 95 through the tubular rock shaft, an arm on the rock shaft, a handle fulcrumed on said arm and engaging the rod to move the same endwise, and a latch carried by the handle and adapted to engage a keeper on the body. 100

5. In a mining machine, the combination of a body, a motor therein, a revolute frame mounted on the forward portion of the body, cutting mechanism mounted in 105 said frame, a drive shaft for said cutting mechanism clutched to the motor, a driving connection between the motor and said frame for revolving the latter, tractor wheels at opposite sides of the body, driving connections between the motor and the 110 wheels for driving the wheels forward or backward at varying speeds and for synchronously rotating the wheels at opposite sides of the body in opposite directions, means extending to the rear of the body for 115 controlling the driving connection to the revolute frame, and means extending to the rear of the body for controlling the driving connections to the tractor wheels.

6. In a mining machine, the combination 120 of a frame, a shaft journaled therein, a frame pivoted on said shaft, cutting mechanism carried by the latter frame and actuatable by said shaft, a gear fixed to the second-named frame, a toothed dog carried 125 by the first named frame and movable into and out of engagement with said gear, and oppositely extending levers for moving said dog.

7. In a mining machine, the combination 130

- of a body, a revoluble frame mounted in front of the body and having a gear, cutting mechanism carried by said frame, a shaft journaled in the body, a pinion fixed to said shaft and intermeshed with said gear, a miter gear on the shaft, a motor in the body, a transverse shaft, spaced miter gears feathered on said shaft and disposed at opposite sides of the first-named miter gear, and means extending to the rear of the body for adjusting said spaced miter gears with respect to the first-named miter gear to effect rotation of the frame in the direction desired.
8. In a mining machine, the combination of a body; a revoluble frame mounted in front of the body and having a gear, cutting mechanism carried by said frame, a shaft journaled in the body, a pinion fixed to said shaft and intermeshed with said gear, a miter gear on the shaft, a motor in the body, a transverse shaft connected with the motor, spaced miter gears feathered on said shaft and disposed at opposite sides of the first-named miter gear and movable with respect to the same, means extending to the rear of the body for adjusting said spaced miter gears; said means including a longitudinal tubular rock shaft and an arm thereon connected with said spaced miter gears, a latch for engaging the gear on the revoluble frame, a lever connected to said latch, and a rod connected to said lever and extending through said rock shaft.
9. In a mining machine, the combination of a wheel-supported body, cutting means carried at the front thereof, longitudinal ducts extending throughout the length of the lower portion of the body at opposite sides thereof, a belt having stretches movable through said ducts and equipped with blades, and also having a forward stretch movable transversely in front of the lower portion of the body and between the same and the cutting means, and means for driving said belt.
10. In a mining machine, the combination of a wheel-supported body, cutting means carried at the front thereof, longitudinal ducts extending throughout the length of the lower portion of the body at opposite sides
- thereof, a belt having stretches movable through said ducts and equipped with blades, and also having a forward stretch movable transversely in front of the lower portion of the body and between the same and the cutting means, means for driving said belt comprising means whereby the connection thereto may be interrupted and reestablished, and means extending to the rear of the body for so interrupting and reestablishing the connection.
11. In a mining machine, the combination of a body, cutting mechanism carried in front thereof, a shaft connected with and adapted to drive said cutting mechanism, a motor in the body and having a drive shaft clutched to the first-named shaft, means for controlling said clutch extending to the rear of the body, a worm on the drive shaft, tractor wheels supporting the body, a transverse shaft having a worm gear intermeshed with said worm, means constructed and arranged to drive said tractor wheels from said transverse shaft at variable speeds and forward or backward or synchronously in opposite directions and means extending to the rear of the body for controlling said drive means.
12. In a mining machine, the combination of a body, a motor therein, a shaft connected with the motor and extending through the front wall of the body, a frame mounted in front of the motor and revoluble about said shaft, a shaft mounted in the frame and disposed at right angles to the first-named shaft, a frame pivoted on the second-named shaft, cutting mechanism carried by said frame and driven from the second-named shaft, cooperating means on the first and second frames for adjustably fixing the latter to the former, a shaft journaled in the body and having a pinion intermeshed with the said gear, a driving connection between the motor and said pinion; said connection being reversible and means at the rear end of the body for controlling said connection.

In testimony whereof I affix my signature in presence of two witnesses.

JAMES A. BRANTLEY.
